Primary Examiner—James R. Largen**Attorney, Agent, or Firm—Timmons & Kelly****[57] CLAIM**

The ornamental design for a splash guard for toilet bowl, as shown and described.

DESCRIPTION

FIG. 1 is a perspective view of a splash guard for toilet bowl showing my new design;

FIG. 2 is a top plan view thereof;

FIG. 3 is a bottom plan view thereof;

FIG. 4 is a side elevational view thereof, the opposite side being the same as the side shown; and,

FIG. 5 is a front elevational view thereof, the rear being the same as the front shown.
